UNITED STATES PATENTS

2,791,814 5/1957 Villela..... 222/559

ABSTRACT: A gas operated stopper for pouring molten metal from a ladle comprising a stationary nozzle seat having an opening therethrough, a movable nozzle positioned in the nozzle seat opening and having a cross section less than the cross section of the opening to form a gap therebetween and a gas operated piston assembly in which the cylinder is secured to the stationary nozzle seat and the piston is secured to the movable nozzle. Compressed air raises the piston and nozzle to remove an extended top section of the nozzle from a mating surface on the nozzle seat and thereby opening a series of inclined passageways leading to a vertically disposed passageway in the nozzle. An inert gas is introduced through the above-identified gap to lubricate the system and prevent molten metal from entering therein.

GAS STOPPER FOR A LADLE

This invention relates to a stopper arrangement for a ladle and more particularly to a stopper for pouring molten metal which is gas operated and which eliminates the stopper rod in the pouring ladle and the like.

While many innovations have been made in the steel industry in recent years, certain age-old problems have continued to plague the basic steel producer. One such problem common to many metal industries is the stopper rod apparatus required in each ladle which is to be used for pouring the molten metal. The basic stopper rod assembly exists today as it did with the early steelmakers. Basically, a nozzle having upwardly extending flanges and an opening therethrough is positioned in an opening called a nozzle well in the bottommost portion of a ladle. The nozzle is held in place by a nozzle plate mounted to the bottom of the ladle and is held firm in the well by ramming a cementitious refractory between the well and the outer nozzle wall. A long refractory wrapped steel rod called a stopper rod vertically extends within the ladle to a steel cross member called a gooseneck above the top of the ladle. The bottom of the stopper rod has a refractory head mounted thereon to cooperate with the inner flanged surface of the nozzle to shut off the nozzle opening. A cumbersome hydraulic cylinder arrangement exists on the outside of the ladle which is connected to the gooseneck to raise and lower it, thus opening and shutting the opening in the nozzle.

All the potential day to day problems associated with stopper rod assemblies are too numerous to mention, but a few of the more routine matters will be cited as representative of the basic problem. After every single pour, a man or crew of men must climb into the ladle after it has cooled to reset the next nozzle. This obviously is time consuming as well as dangerous. In addition, very small errors in setting the nozzles can have catastrophic effects. For example, if the stopper rod is not perfectly aligned with the stopper head which in turn is not perfectly aligned with nozzle opening in the nozzle which in turn is not perfectly aligned in the nozzle well, improper shutoffs of varying degree can occur during teeming. Similar shutoff problems occur from bent stopper rods which occur under a variety of use conditions. This improper shutoff can range from a completely plugged nozzle opening where no metal can be poured to a leaky molten metal spraying stream to a full running stopper which defines a condition when the stopper head does not cover the nozzle opening at all and the metal gushes out of the nozzle opening uncontrolled. In addition, present stopper heads provide a relatively small surface area of contact with the nozzle itself, which often leads to insufficient shutoffs.

My invention completely eliminates the stopper rod assembly. Therefore, all the problems associated with this cumbersome method of controlling steel pouring are eliminated. My invention can be installed from the outside of the ladle, thus eliminating a hazardous job as well as saving considerable time. My invention can be prefabricated saving the steel mill the time and problem of assembly. My invention includes a gap between the nozzle and the nozzle seat which permits expansion and contraction without causing harm. This gap provides a passageway for an inert gas lubrication system and also a purge of the steel in the ladle. This gap also permits an oxygen purge to clean the nozzle should it become necessary. My invention further provides for the contact of relatively large surface areas to close off the pouring of the molten metal.

My invention is a gas stopper for a pouring ladle and the like having a stationary nozzle seat, a nozzle assembly and a piston assembly. At least a portion of the nozzle assembly is movable to open and close passageways connecting the interior of the ladle with a central opening through the nozzle. A compressed fluid actuates the piston which is associated with the movable portion of the nozzle assembly. An inert gas lubricates the system and also prevents molten metal from entering therein.

In the accompanying drawings, I have shown the present preferred embodiments of my invention in which:

FIG. 1 is a vertical section through my gas stopper mounted in a pouring ladle and shown in the open position;

FIG. 2 is a section through lines II-II of FIG. 1;

FIG. 3 is a vertical section through another embodiment of the nozzle;

FIG. 4 is a vertical section through another embodiment of my gas stopper shown in the closed position;

FIG. 5 is a vertical section through still another embodiment of my gas stopper shown in the open position; and

FIG. 6 is a plan view of the gas stopper of FIG. 5.

While it will be obvious that my gas stopper is amenable to many applications, I will direct my embodiments to the metal industry and more particularly the steel industry, in which my disclosure is particularly pertinent.

I have shown my gas stopper 1 positioned in the nozzle well 10 in the bottommost portion of teeming ladle 2, see FIG. 1.

This ladle, of course, could be of a transfer ladle, a tundish or any other type of ladle from which molten metal is poured. My gas stopper 1 comprises three major components, the nozzle seat 3, the nozzle assembly 4, and the gas operated piston assembly 5.

The nozzle seat 3 is an annular walled refractory which is securely positioned in the nozzle well 10 of ladle 2. Nozzle well 10 is generally the circular area between the opening through the bottom of the ladle 2 and the first full layer of brick 11 in the bottom of ladle 2. Nozzle seat 3 is secured in place by nozzle plate 6 which supports the bottom of the nozzle seat 3 and which is bolted to the bottom side 7 of ladle 2 by bolts 8. The annular wall 9 of nozzle seat 3 is flush against the first full layer of brick 11 in the ladle. To insure the secureness of the positioning of nozzle seat 3, a cementitious refractory (not shown) is rammed between the wall 9 and the brick 11 to completely fill the nozzle well 10. The nozzle seat 3 has a centrally disposed vertical opening 13 completely therethrough. The opening 13 which accommodates the nozzle 12 has a slightly larger cross section than the tubular wall 14 of nozzle 12 so when the nozzle 12 is in place, as will be described hereinafter, a small gap 45 is present in opening 13 between the tubular wall 14 of nozzle 12 and the nozzle seat 3. The upper surface 15 of nozzle seat 3 is slanted toward the centrally disposed opening 13. Extending upwardly from slanted upper surface 15 is seating lip 16 which, as will be seen and described hereinafter, represents the surface area of the nozzle seat which contacts the nozzle assembly to shut off the molten metal pour. The bottom surface of the nozzle seat has a recessed threaded section 22 to cooperate with the gas operated piston assembly. Even after the gas operated piston assembly is mounted to the nozzle seat 3 at threaded recess section 22, a space 44 remains in the recess.

The major component of the nozzle assembly 4 is the nozzle 12 which is slidably positioned within opening 13 in the nozzle seat 3. Nozzle 12 which is made of a refractory such as fire clay is tubular in shape and, as shown in FIG. 1, has a centrally disposed opening 17 extending the length of the nozzle 12. Three equally spaced passageways 19 extend through the tubular wall 14 of nozzle 12 and exit angularly into opening 17, see FIGS. 1 and 2. These passageways 19 direct the molten metal from the ladle 2 into the centrally disposed opening 17. The bottom section of the nozzle has threads 23 to cooperate with the gas operated piston assembly 5 and the top section of the nozzle has threads 20 to cooperate with refractory cap 18 hereinafter described. Refractory cap 18 having internal threads 54 is mounted on the upper portion of nozzle 12 by cooperating nozzle threads 20. Cap 18 has an angularly disposed bottom seating surface 21 with respect to the walls of nozzle 12 which is positioned substantially in line with the top surface of angular passageways 19.

The nozzle assembly can be one single unit, as shown in FIG. 3, instead of a separate nozzle and cap. Similar parts are represented by identical numerals but having a prime located thereafter. In FIG. 3 the one piece nozzle 12' has a centrally disposed opening 17' which extends slightly above the angularly disposed passageways 19'. The cap section 18' is identical to cap 18 of FIG. 1 except, of course, there are no internal threads since the head section is integral with the nozzle 12'. Whether the nozzle is a single unit, as in FIG. 3, or includes a

separate cap 18 is merely a choice of design based upon cost and ease of fabrication of the respective units.

The gas operated piston assembly 5 is positioned outside of ladle 2 beneath the ladle bottom 7 and is mounted to nozzle seat 3. The piston assembly 5 comprised of all metal parts, has an annular cylinder wall 24 having threads 25 at its upper end which cooperate with threaded recess 22 in the nozzle seat 3 to stationarily secure the assembly 5 thereto. The wall 24 which extends completely around seat opening 13 and nozzle 12 has an inwardly disposed flange 26 around its inner surface 27 which serves as the upper limiting position for the piston. The wall 24 has a lower section 28 extending perpendicular from the vertical section mounted to the seat 3 at the bottom thereof and toward the nozzle 12. Section 28 in turn has a downwardly extending section 39 perpendicular to section 28. The inner surface 27 of the wall 24 and the wall section 28 form a part of cylinder chamber 29. A metal piston 30 operates within the cylinder chamber 29. Piston 30 is comprised of an annular shaft 33 which extends around nozzle 12 and an annular arm 32 which extends from the top of piston shaft 33 to the inner surface 27 of wall 24. Shaft 33 completes the cylinder chamber 29 in which piston arm 32 acts as the piston head. The bottom portion of piston shaft 33 has threads 31 which cooperate with lower threads 23 of nozzle 12 to secure the piston 30 to the nozzle 12. The piston shaft 33 and arm 32 are dimensioned so that the end of outwardly extending arm 32 slides along inner surface 27 of wall 24 which forms the inner cylinder wall. The stroke of the piston is limited at its upper end by flange 26 of wall 24 and is limited at its lower end by the extending lower section 28 of wall 24. The piston shaft 33 slides against the downwardly extending wall section 39.

A threaded, compressed air inlet 34 positioned near the bottom of wall 24 leads into passageway 35 which extends completely through the lower section 28 of wall 24 and into the cylinder chamber 29. An adjustable needle valve 36 is positioned in passageway 35 and extends out of lower section 28 to control the air input into cylinder 29. Two sealing rings 37 are secured to arm 32 to prevent leakage of the compressed air in cylinder 29 as arm 32 slides along inner wall 27. Two similar sealing rings 38 are recessed in the end of extended wall section 39 to provide an adequate seal between section 39 and sliding piston shaft 33.

The piston shaft 33 has a vertical inert gas passageway 40 leading vertically through the bottom section of the piston shaft 33 and continuing as recess 41 along the surface of shaft 33 which faces nozzle 12. Gap 45 between the nozzle 12 and nozzle seat 3 also extends downwardly between the piston shaft 33 and the nozzle 12. Therefore, passageway 40 which leads into recess 41 communicates with gap 45. Passageway 40 has inlet means 42 extending through the bottom of downwardly extending portion 33 of piston 30. A lock bolt 43 extends through downwardly extending wall portion 39 to lock the piston shaft 33 against wall 39 in the closed position when the ladle is being filled.

The operation of my gas stopper shown in FIG. 1 is as follows: while the ladle is being filled with molten metal, the nozzle is in the closed position, as shown in FIG. 4, for a slightly different embodiment of my invention. In the closed position, the bottom seating surface 21 of cap 18 is in intimate contact with eating lip 16 of nozzle seat 3. This completely shuts off passageways 19 from the molten metal in the ladle. The weight of the molten metal on cap 18, gravity acting on nozzle 12 and lock bolt 43 all insure that nozzle 12 remains in the closed position. After the ladle is filled and teeming is ready to commence, lock bolt 43 is loosened and compressed air is fed through passageway 35 into cylinder chamber 29. This compressed air forces piston arm 32 upward until it contacts lip 26 of wall 24. Since the lower portion of piston shaft 33 is connected to nozzle 12, the nozzle 12 also moves upwardly removing the bottom seating surface 21 of cap 18 from lip 16 and permitting the molten metal to flow through into passageways 19 and through nozzle opening 17.

Simultaneously with the opening of compressed air passageway 35, inert gas passageway 40 is opened. This causes the inert gas such as argon to flow upwardly into gap 45. The pressure of the inert gas is maintained sufficiently high to prevent any molten metal from entering gap 45. The inert gas then bubbles into the molten metal. If the inert gas system is operated when the nozzle 12 is in the closed position, the inert gas enters recess 44, the excess space about the lower surface of nozzle seat 3, and exerts pressure on the top of piston arm 32 to help maintain the nozzle assembly 4 in the closed position.

It will be recognized by those skilled in the art that the mating surface areas 21 and 16 of cap 18 and nozzle seat 3, respectively, in intimate contact with each other to keep gas stopper 1 in the closed position is much greater than the surface area between the mating surfaces of a standard nozzle and stopper head presently employed.

In addition, it can be seen that the inert gas such as argon passing through gap 45 acts as a lubricant to permit easy movement of nozzle 12. It is also recognized that bubbling an inert gas through molten metals such as steel has many beneficial effects such as purging the steel by acting as nucleation sites for removing other entrapped gases in the molten metal. The gap 45 also permits uninhibited expansion and contraction of the various members whose surfaces define the gap.

Another embodiment of my invention is shown in FIG. 4. The only modification in this embodiment is in the gas operated piston assembly. The cylinder chamber 53 is formed of four separate annular metal walls. The top of chamber 53 is defined by annular shaped wall 46 which has threads 25' at its upper end to cooperate with recessed threaded section 22' of nozzle seat 3' to secure the cylinder chamber 53 to the nozzle seat 3'. The annular vertical walls 47 and 48 both of which are welded to wall 46 form the outer and inner sidewalls respectively of chamber 53. Base wall 49 which is welded to outer wall 47 forms the bottom of cylinder chamber 53. The inner wall 48 has its outer surface aligned with wall 46 and nozzle seat 3' to define the opening for the nozzle 12' and the resultant gap 45'. The piston 30' has an additional surface of the chamber 53 to slide on, namely, inner wall 48 and therefore, additional seal rings 50 are positioned in wall 48 to maintain the adequate seal.

Threaded, compressed air inlet 34' extends through sidewall 47 and base wall 49 and leads into passageway 35' which exits into chamber 53 below piston arm 32'. A similar compressed air passageway 51 in wall 46 exits into chamber 53 above piston arm 32' from compressed air inlet 52 which extends through the upper part of wall 47 and wall 46. With this embodiment, the raising of the piston and nozzle is the same as the embodiment of FIG. 1. The lowering of the nozzle to the closed position, as shown in FIG. 4, however, is accomplished by entering compressed air through passageway 51 which forces piston arm 32', piston shaft 33' and nozzle 12' downwardly causing seating surface 21' of cap 18' to contact seating lip 16' of nozzle seat 3' and shut off passageways 19' from the molten metal in the ladle.

A further embodiment of my invention is shown in FIGS. 5 and 6. In this embodiment, the nozzle itself is stationary, and a refractory piston operating within a chamber in the nozzle wall opens and closes the passageways leading from the ladle into the central nozzle opening.

A refractory cap 60 is permanently positioned above the nozzle opening 61 of nozzle 62 by securing it within the ladle 2' on the ladle bottom. Cap 60 has annular sides 63 which act as the nozzle seat and which completely fill the annular nozzle well 64. Again, a cementitious refractory (not shown) can be rammed between sides 63 and nozzle well 64 to secure the block in place.

Nozzle 62 having a tubular wall 65 is positioned in the opening in the bottom of the ladle 2' and is held in place by both the nozzle plate 67 bolted to the bottom side 68 of the ladle 2' by bolts 69 and the nozzle seat sides 63. The passageway 61 of the nozzle 62 vertically extends completely therethrough.

Cap 60 has three equally spaced passageways 71 leading through the cap to an opening 72 directly above the opening 61 of nozzle 62 and which is defined by the space between the convexly curved inner bottom surface 70 of cap 60 and upper surface 74 of nozzle 62.

A vertically disposed annular chamber 73 extends within the tubular wall 65 of nozzle 62 from upper nozzle surface 74 to a point in the nozzle which is below the bottom side 68 of the ladle. A compressed inert gas inlet 75 and connecting passageway 76 communicates with the bottom of chamber 73. A second inert gas inlet 78 and connecting passageway 79 communicate with chamber 73 about midway between its ends and just below the bottom side 68 of the ladle. An annular refractory piston 80 having a length substantially equal to the depth of chamber 73 is loosely fitted in chamber 73 to form a gap 77 therebetween. Piston 80 has a small recess 81 at its bottom end which communicates with passageway 76 and a second larger recess 82 which is intermediate the piston ends and communicates with passageway 79. The upper surface 83 of piston 80 is sloped toward nozzle passageway 61 to mate with the convex surface 70 of cap 60.

An inert gas such as argon is entered into recess 81 through passageway 76. The gas forces piston 80 upward until the upper surface 83 of piston 80 contacts the convex surface 70 of cap 60. This completely shuts off passageways 71 from space 72 and opening 61 in nozzle 62. Because of the gap 77 between the nozzle chamber 73 and the piston 80, argon escapes along the sides of piston 80 and out into the molten metal entering through passageway 71. The pressure of the argon is sufficiently maintained to insure that no metal gets into the gap 77. To lower piston 80 and permit metal flow through passageways 71, argon is introduced through passageway 79 into recess 82 simultaneously as the flow of argon is decreased from passageway 76. The increase and decrease of argon flow in the respective chambers is synchronized to maintain a sufficient flow of argon in the gap 77 to prevent any molten metal from getting g therein. As in the other embodiments, this argon escapes into the molten metal.

I claim:

1. A gas operated stopper for a pouring ladle comprising:
  - A. A nozzle seat having a central opening and adapted to be secured in a nozzle well of the ladle;
  - B. A nozzle assembly positioned within the opening in the nozzle seat and having a central opening therein, at least a portion of the nozzle assembly being movable into and out of contact with the nozzle seat;
  - C. Said nozzle assembly and said nozzle seat being constructed and positioned to provide a passageway connecting the interior of the ladle and the central opening in the nozzle assembly when the movable portion of the nozzle assembly is out of contact with the nozzle seat to allow liquids to flow from the interior of the ladle, through the passageway and out the central opening in the nozzle assembly;
  - D. A gas actuated piston member associated with the nozzle assembly, said piston forming the movable portion of the nozzle assembly into and out of contact with the nozzle seat to open and close the passageway between them whereby the flow of liquids is regulated; and
  - E. A second passageway surrounding the movable portion of the nozzle assembly providing a channel for the flow of inert gas to lubricate said moving member.
2. A gas operated stopper for a pouring ladle comprising:
  - A. A nozzle seat adapted to be secured in a nozzle well of the ladle and having a central opening therethrough and a seating surface surrounding the central opening;
  - B. A movable nozzle assembly having:
    1. a tubular body portion having a vertically disposed opening therethrough and positioned in the opening in the nozzle seat and having cross section smaller than the opening to provide a gap between the seat and the body portion of the nozzle assembly;

2. a cap portion on top of the tubular body portion having a cross section larger than the cross section of the body portion and having a seating surface surrounding the body portion positioned to mate with the seating surface on the nozzle seat; and

3. at least one passageway extending through the wall of the tubular body portion below the seating surface of the cap portion into the vertically disposed opening;

C. A piston assembly having:

1. a cylinder secured to the nozzle seat and having a fluid passageway communicating therewith;

2. a piston mounted for movement within the cylinder and secured to the movable nozzle, fluid entering the cylinder through said fluid passageway raises the piston and nozzle, separating said seating surfaces and permitting liquid to flow from the ladle through the passageway in the tubular body portion of the nozzle and through the nozzle opening; and

D. An inlet connecting with the gap for supplying inert gas thereto, said inert gas lubricating the system and preventing molten metal from entering therein.

3. The gas stopper of claim 2 wherein the cylinder has an outer surface parallel with the nozzle and axially aligned with a portion of the nozzle seat which defines the central opening to thereby longitudinally extend the gap between the body portion of the nozzle and the nozzle seat.

4. The gas stopper of claim 2 wherein the seating surface of the nozzle seat has a raised lip extending upwardly therefrom to cooperate with the seating surface of the cap portion of the nozzle assembly.

5. The gas stopper of claim 2 wherein the cap portion is a separate refractory cap secured to the upper section of the nozzle.

6. The gas stopper of claim 2 wherein a second fluid passageway communicates with the cylinder at substantially the top thereof, whereby fluid forces the piston and connected nozzle downwardly so that the seating surface of the cap portion of the nozzle assembly mates with the seating surface of the nozzle seat.

7. The gas stopper of claim 2 wherein the cylinder has an upper threaded end which cooperates with threads in a recessed area in the bottom of the nozzle seat, said recessed area communicating with said gap, whereby gas enters said recessed area when the seating surfaces are mated to define a closed position to exert a pressure on the top of the piston to maintain said closed position.

8. The gas stopper of claim 2 wherein the passageway extending through the wall of the tubular body portion is inclined to the vertically disposed opening in the tubular body portion.

9. The gas stopper of claim 2 wherein the cylinder is annularly disposed about the tubular body portion of the nozzle and the piston is annularly shaped for movement within the cylinder.

10. The gas stopper of claim 3 wherein a piston shaft of the piston forms the outer surface of the cylinder which parallels the nozzle and is axially aligned with that portion of the nozzle seat defining the nozzle seat central opening.

11. The gas stopper of claim 10 wherein a lock bolt extends through a lower section of the cylinder and is adaptable to contacting the piston shaft to prevent movement of the piston in the cylinder.

12. The gas stopper of claim 10 wherein said gap connecting inlet extends through the shaft of the piston.

13. A gas stopper for a ladle comprising:

A. A nozzle seat having a central opening therethrough and stationarily secured in the ladle, said vertical opening axially aligned with an opening through the bottom of the ladle, said nozzle seat having a refractory cap positioned above the central opening and at least one passageway extending through said nozzle seat and communicating with said central opening;

B. A tubular nozzle stationarily secured within the vertical opening in the nozzle seat, said nozzle having:

1. a centrally disposed passageway therethrough;
  2. an annular chamber vertically disposed from the top surface of the nozzle into the tubular wall and about said centrally disposed opening; and
  3. a first and second gas passageway through the wall of the nozzle, said first passageway communicating substantially at the bottom of said chamber and said second passageway communicating with said chamber between the ends thereof; and
- C. An annular refractory piston loosely positioned in said chamber to form a gap therebetween, said piston having an upper surface adapted to mate with an inner surface of the cap and a first and second recess, the first recess communicating with the first gas passageway and the second
